EARTH SCRAPER

Philip C. Anderson, Rapid City, S. Dak.

Application December 24, 1934, Serial No. 758,931

3 Claims. (Cl. 37—140)

This invention relates to an earth scraper of the type commonly known as a "Fresno", that is, a scraper adapted to be drawn over the ground so as to scrape up a load of earth, rock or other material, and provided with a handle or "Johnson bar" by means of which the forward edge may be brought into engagement with the ground so that the pulling force will invert the scraper to dump the contents thereof. When in 10 the inverted position, the scraper rides upon forwardly extending runners which support it out of engagement with the ground.

The principal object of this invention is to provide highly efficient and long wearing protecting 15 shoes for these runners so as to prevent wear and damage thereto.

Another object of the invention is to so construct the protecting shoes that they can be easily attached or detached and, when in place, 20 will be rigidly and firmly locked to the runners against both lateral and longitudinal displacement.

A further object is to so construct the shoes that they will be adaptable to all runners regardless of the spacing of the bolt holes therein, 25 so that they will firmly hold the bolts while the nuts are being tightened or removed and so that they will allow the bolts to be easily removed should it be desired to replace or renew the 30 shoes.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a perspective view illustrating a typical scraper of the "Fresno" type with the invention applied thereto.

Fig. 2 is a plan view of the upper extremity of one of the protecting shoes.

Fig. 3 is a cross section through the shoe and runner taken on the line 3—3, Fig. 2.

Fig. 4 is a cross section through an alternate type of shoe.

The drawing illustrates at 10 a typical "Fresno" scraper with its "Johnson bar" at 11, runners at 12, and draw bar at 13. The runners are each provided with two bolt holes for the attachment 55 of shoes and their forward extremities are curved

to provide arcuate running surfaces when the scraper 10 is in the inverted or discharging position. In use these surfaces rapidly wear away from the constant friction with the earth, sand, gravel, etc.

Attempts have been made to place shoes upon these surfaces, but these attempts have not been practical. The bolt holes are not spaced uniformly since the distortion in bending the runner and differences in manufacture etc., places the 10 bolt holes at varying positions. Therefore the usual shoes must be drilled to fit the particular runner upon which they are to be placed, thus involving delays, expense and inconvenient field work. In the usual shoes, the bolts must be well 15 counter-sunk or their heads will be quickly worn away. These counter-sunk bolts become loosened and their nuts rusted in place, and it is impossible to remove the bolts or tighten the nuts since the bolt heads will revolve in the round, counter- 20 sunk holes. Therefore to replace an ordinary shoe or even tighten the bolts thereof, it is necessary to cut the bolts from place and replace them with new ones, causing considerable delay in use. The usual shoes also frequently work to one side 25 or another, putting the scraper temporarily out of service.

This invention is designed to eliminate all of the above troubles and provide a shoe which will be held positively and permanently and yet with 30 which the bolts can be easily and quickly tightened or removed and in which any spacing of bolt holes which may be found in a runner can be accommodated with a single standard shoe.

The improved shoe is illustrated at 14 and is 35 curved to fit the average curve of the runners 12. The back of the shoe is inset to receive the runner so that two holding flanges 15 are formed along the inner edges which firmly engage the sides of the runner 12 and prevent the shoe from 40 slipping laterally from place thereon. The shoe is preferably formed of a wear resisting cast metal, which will outlast many ordinary sheet metal or structural metal shoes. The flanges 15, in addition to providing means for holding the 45 shoe in place, greatly increase the structural strength thereof and provide sufficient strength even though the runner surface may be well worn down as the flanges themselves can never be subjected to wear.

Each extremity of the shoe is tapered to a relatively sharp edge as shown at 19 so as to provide a smooth continuous rocking or rolling surface. The mid-portion of the shoe which is subjected to the greatest wear is relatively thicker than the 55

end portions thereof. The extremities are formed with inwardly extending bolt slots 16. The slots 16 are sufficiently long to accommodate the minimum bolt hole spacing to be found in scraper runners. The outer edges of the upper slot 16 are formed with a series of triangular depressions or notches 17 for engaging the corners of a square head bolt such as indicated at 18.

This construction serves a triple purpose, first 10 it prevents the bolt from turning while the nuts are being tightened or loosened; second, it prevents the shoe from shifting vertically or longitudinally on the runner since the engagement of the bolt head in the triangular depressions prevents any longitudinal shifting of the shoe; and third, it allows a standard shoe to be fitted onto any runner regardless of the bolt hole spacing.

It is preferred to employ the triangular notches 17 in the upper slot 16 only so that the shoe can 20 be shifted at the lower slot to accommodate any fractional spacing of the bolts between the notches 17. However, if it is desired, the triangular notches may also be provided at the bottom slot 16.

25 The shoe 14 may be formed with a wider tread than the usual runner 12 for use in soft earth, etc. This gives a greater wearing surface, as well as preventing the shoe from swinging into the ground. Such a shoe is indicated in cross section 30 in Fig. 4, in which the socket for receiving the runner 12 is indicated at 20 and the wide bottom tread is indicated at 21.

While a specific form of the improvement has been described and illustrated herein, it is desired

to be understood that the same may be varied, within the scope of the appended claims, without departing from the spirit of the invention.

Having thus described the invention, what is claimed and desired secured by Letters Patent 5 is:—

1. A wearing shoe for "Fresno" scrapers comprising: an arcuate channel member having slots extending inwardly from each of its extremities for receiving bolts to attach said member to said 10 runner; and a series of triangular, oppositely-placed notches along the edge of one of said slots for engaging the corners of a bolt head.

2. A protecting shoe for the curved portions of the runners of a "Fresno" scraper comprising: a 15 curved cast shoe of greater thickness at its middle than at its extremities and having a channel formed in its rear or concave surface for receiving a runner; and inwardly extending longitudinal slots along the center line of the wearing 20 surface and at each extremity of said shoe for receiving bolts to attach said shoe to said runner.

3. A protecting shoe for the curved portions of the runners of a "Fresno" scraper comprising: a curved cast shoe having a channel formed in 25 its rear or concave surface for receiving a runner; inwardly extending longitudinal slots at each extremity of said shoe for receiving bolts to attach said shoe to said runner; and a series of countersunk depressions or notches along the opposite 30 edges of one of said slots for receiving the head of a bolt.
